[57] ABSTRACT

A slide fastener having a filling core adapted to stabilize the position of the fastener coupling elements when mounted on the stringer tapes of the fastener. The core is made from a fabric of a knitted structure having at least wales and an inter-wale groove defined therebetween, the arrangement being that stitchings securing the elements to the tapes run through the core along the inter-wale therein without causing the core to become deformed or displaced relative to the longitudinal axis of the fastener.

SLIDE FASTENER HAVING A FILLING CORE

BACKGROUND OF THE INVENTION

This invention relates to slide fasteners of the type having a series of integrally united coupling elements formed from a filamentary plastic material and secured to an inner longitudinal edge of each of a pair of stringer tapes. More particularly, the invention is concerned with slide fasteners of the class described which further includes a filling or reinforcing core utilized to stabilize the position of the coupling elements when secured as by stitching to the stringer tape.

Heretofore, there have been proposed many filling cores of different forms and constructions that are made from stranded, braided or plaited pieces of textile cloth having a round or flattened cross-section. Such prior-art filling cores have suffered from the disadvantage that the core was deformed and moved in a serpentine fashion relative to the longitudinal axis of the fastener when it was subjected to pressure of the sewing needle that sews the same together with fastener coupling elements to the tape. This resulted in irregular gaps or clearances wherein adjacent coupling elements are interengaged or intermeshed, which would therefore disapprove the constant, uniform strength of coupling between the elements throughout the length of the fastener and would often invite a rupture in the chain of fastener elements.

SUMMARY OF THE INVENTION

It is therefore the primary object of the present invention to provide a slide fastener which will eliminate the aforesaid disadvantages of the prior-art fastener.

A more specific object of the invention is to provide a filling core which is free from objectionable deformation or displacement relative to the longitudinal axis of the fastener when sewn together with the fastener coupling elements to the tape, and which will therefore serve to maintain uniform strength of coupling between the elements throughout the length of the fastener.

These and other objects and features of the invention will become apparent from the following detailed description of certain preferred embodiments taken in conjunction with the accompanying drawings wherein like reference characters or numerals refer to like and corresponding parts throughout the several views.

BRIEF DESCRIPTION OF THE DRAWINGS

FIG. 1 is a fragmentary, partly broken away, plan view on enlarged scale of the reverse side of a slide fastener according to the invention;

FIG. 2 is a transverse cross-sectional view taken along the line II-II of FIG. 1, showing the two stringer tapes coupled together;

FIG. 3 is a transverse cross section of one of the two stringer tapes, showing a modified form of the invention; and

FIGS. 4 through 7 inclusive are views similar to FIG. 3 but each showing a different modification according to the invention.

DESCRIPTION OF THE PREFERRED EMBODIMENTS

Referring now to the drawings and FIGS. 1 and 2 in particular, there is shown a slide fastener F which comprises a pair of opposed stringer tapes T₁, T₂, each carrying along their respective inner longitudinal edges a

series of integrally united coupling elements E which are engaged and disengaged by a slider (not shown) to close and open the fastener in the usual manner.

The coupling elements E are formed from a filamentary plastic material into a coiled structure wherein each of the elements E has a coupling head portion Ea, two spaced apart transversely extending leg portions Eb₁, Eb₂ and a base portion Ec connecting the leg portions Eb of each element to those of adjacent elements.

Designated at 10 is a filling core according to the invention which is inserted in the space between the upper and lower leg portions Eb₁ and Eb₂ and extends longitudinally throughout the length of the series of elements E and substantially parallel with the longitudinal axis of the stringer tape T₁, (T₂). The filling core 10 is made of a knitted fabric having at least two longitudinally extending wales 10a defining therebetween an inter-wale groove 10b.

Designated at 10 is a filling core according to the invention which is inserted in the space between the upper and lower leg portions Eb₁ and Eb₂ and extends longitudinally throughout the length of the series of elements E and substantially parallel with the longitudinal axis of the stringer tape T₁, (T₂). The filling core 10 is made of a knitted fabric having at least two longitudinally extending wales 10a defining therebetween an inter-wale groove 10b.

In the embodiment shown in FIGS. 1 and 2, the filling core 10 is inserted between the leg portions of the elements with the inter-wale groove 10b directed towards the lower leg portions Eb₂ that engages with the surface of the stringer tape T₁, (T₂). The core 10 is accommodated in and extends longitudinally of the series of elements E such that it fills the part of the space between the two leg portions Eb₁, Eb₂ which lies in the proximity of the base portion Ec but leaves unfilled the part of the space which lies in the proximity of the coupling head portion Ea to provide a sufficient clearance 11 thereat for interengagement of the elements E on the opposed stringer tapes T₁ and T₂. The wales 10a of the core 10 serve as a guide for a sewing needle (not shown) in such a way that the latter runs exactly into and along the inter-wale groove 10b. It will be readily understood that the needle can thrust, with a minimum of resistance, through the groove portion of the core 10 which is relatively thin and hence does not cause the core 10 to become deformed or move sidewise to interfere with

interengagement of the coupling elements E. Thus, the provision of the filling core 10 characteristic of the invention ensures that the clearance 11 extending transversely of the elements E is maintained unvaried and aligned parallel with the longitudinal axis of the fastener F throughout the length of the elements E whereby the strength of coupling between adjacent elements E is held constant.

The series of elements E are sewn as by a lock stitching S₁ to the respective stringer tapes T₁ and T₂ along the line of seam S which registers with the longitudinally extending grooves 10b between the wales 10a.

FIG. 3 illustrates a modification wherein the core 10 is inserted in the elements E with the wales 10a facing the upper leg portion Eb₁ contrary to the embodiment shown in FIGS. 1 and 2.

The embodiment shown in FIG. 4 is characterized by the provision of a filling core 10 having three wales 10a and hence two inter-wale grooves 10b and a covering strip 12 of similar construction to the core 10 laid over the upper leg portions Eb₁ of the elements E, both core and strip being secured together with the elements E to the tape T₂ by means of two-thread chain stitches S₂ as shown.

The embodiment of FIG. 5 employs a filling core 10 similar to that shown in FIG. 4, which core is secured together with the elements E to the tape T₂ by means of two needle lock stitches S₃.

FIG. 6 illustrates a further modification wherein the elements E are mounted on a stringer tape T_2 of a knitted structure and sewn thereto through a filling core 10 having two wales 10a, the stitchings being accommodated in a recess 13 formed in the upper leg portions Eb₁.

The embodiment shown in FIG. 7 is characterized by the application of a filling core 10 to a serpentine form of coupling elements E which are secured together with the core 10 by two needle lock stitches S₃.

Having thus described the invention, it will be understood that various changes may be made in the specific form and construction described above and illustrated in the drawings without departing from the scope of the appended claim. As for an example, the number of wales 10a and inter-wale grooves 10b may be increased depending upon the size of the elements E employed.

What is claimed is:

1. A slide fastener comprising a pair of opposed stringer tapes, a series of integrally united coupling elements secured to the inner longitudinal edge of each of

the opposed stringer tapes, said coupling elements each having a coupling head portion, spaced apart upper and lower leg portions and a base portion connecting said leg portions of each element to those of adjacent elements, a filling core having at least two wales and an inter-wale groove defined therebetween, said core being inserted in the space between said upper and lower leg portions and extending longitudinally throughout the length of said series of coupling elements and parallel with the longitudinal axis of the fastener, and stitchings running through said core along said inter-wale groove and securing said elements together with said core to the respective stringer tapes.

10 2. A slide fastener as defined in claim 1 wherein said filling core is made from a knitted fabric.

15 3. A slide fastener as defined in claim 1 wherein said filling core is inserted with said wales directed towards said lower leg portions of the coupling element.

4. A slide fastener as defined in claim 1 wherein said filling core is inserted with said wales directed towards said upper leg portion of the coupling element.
